UNITED STATES PATENT OFFICE.

WILLIAM M. PFITZNER, OF BROOKLYN, ASSIGNOR TO THE PALMER MANUFACTURING COMPANY, OF NEW YORK, N. Y.

DESIGN FOR A PLAQUE.

SPECIFICATION forming part of Design No. 17,065, dated January 11, 1887.

Application filed February 24, 1886. Serial No. 193,091. Term of patent 14 years.

To all whom it may concern:

Be it known that I, WILLIAM M. PFITZNER, a citizen of the United States, residing at Brooklyn, in the county of Kings and State of New York, have invented and produced a new and original Design for Plaques, of which the following is a specification; and I do hereby declare the following to be a full, clear, and exact description of the invention, such as will enable others skilled in the art to which it appertains to make and use the same.

In the accompanying drawings, forming a part of this specification, Figure 1 is a perspective view of a plaque embodying my design, and Fig. 2 is a central cross-section of the same.

The leading feature of my design consists in a plaque having a central plain field of slightly dulled surface and separated from the border of the plaque by an intermediate depressed shoulder or rib angular in cross-section, which relieves and separates the plain field from the border, which latter projects upwardly outside the said shoulder.

A is the border of the plaque, consisting of the following members: an edge rim, *a*, an ogee molding, *b*, and a concave, *c*, having a fillet, *d*, near its lower edge.

B is the central plain field, usually concave, and having a slightly dull surface. C is an intermediate angular depressed rim between border A and central plain field B. This additional member C gives great additional beauty of form to the plaque.

I claim—

The design for a plaque, as herein shown and described, the same consisting of a plaque provided with a depressed concave central field having a slightly dull surface surrounded by a rib or shoulder, beyond which the border projects upwardly, as set forth.

In testimony whereof I here affix my signature in presence of two witnesses.

WILLIAM M. PFITZNER.
